UNITED STATES PATENT OFFICE.

LEONARD SHAW, OF MIAMI, FLORIDA.

SPRINKLER.

1,239,230.

Specification of Letters Patent. Patented Sept. 4, 1917.

Application filed August 18, 1915. Serial No. 46,132.

To all whom it may concern:

Be it known that I, LEONARD SHAW, a citizen of the United States of America, and a resident of Miami, county of Dade, 5 and State of Florida, have invented certain new and useful Improvements in Sprinklers, of which the following is a specification.

This invention relates to sprinklers and 10 particularly to the kind which is designed mainly for irrigation purposes and for the prevention of frost.

The main objects of the invention are to 15 simplify and improve the construction of sprinklers whereby their efficiency is increased, leakage is avoided between the rotary and stationary parts of the sprinkler, and mechanical friction is eliminated between the rotary and stationary parts, and 20 to provide certain improvements in sprinkling devices of the "velocity" type such as is described and claimed in my copending application Serial No. 863,290, filed September 24, 1914.

25 An illustrative embodiment of this invention is shown in the accompanying drawings, in which—

Figure 1 is a transverse vertical section of 30 a sprinkler constructed according to this invention.

Fig. 2 is a plan of the same.

Fig. 3 shows in elevation an attachment 35 for producing a fine spray, and which may be substituted for the rotary element of the sprinkler shown in Fig. 1.

Fig. 4 shows in detail a modification of one of the deflecting cones appearing in Fig. 3.

Fig. 5 is a vertical section showing a 40 modification of the sprinkler.

Fig. 6 is a vertical section showing another modification.

Sprinkling devices as now commonly made have a rotary nozzle member in which 45 the passages are so formed as to give rise to static pressure in the water flowing therethrough and this causes leakage at the bearing between the rotary and stationary parts of the sprinkler. In such pressure operated sprinklers there is also more or 50 less loss, due to mechanical friction at the bearings.

The present device is so proportioned as to eliminate the possibility of any appreciable static pressure occurring in the rotary 55 nozzle member thereof, and is also arranged

to support the rotary member in frictionless relation to the supporting or stationary member of the nozzle.

Fig. 1 of the drawings shows a form 60 of the sprinkler which comprises a rigid supporting member 1, threaded at 2 for connection with a supply pipe and properly tapered at 3 toward its outlet 4 to form a nozzle for producing a vertical jet of considerable velocity. The member 1 also supports a pipe 5 communicating therewith and suitably bent as shown in Fig. 1 to direct a jet of water downwardly in the axial line of the outlet 4 of the member 1. The pipe 65 5 at its outlet end is provided with a nozzle 6 having a reduced aperture 7 for the purpose of increasing the automatic balance of the nozzle member 8.

The rotary nozzle member 8 has a bell 75 shaped mouth 9 at its lower end near the outlet 4 of nozzle member 1, and at its upper end is provided with a conical spray deflector 10, the tip of which enters the enlarged opening 11 in the end of nozzle 6. 80 The rotary member 8 comprises two or more tubular arms 12 and 13 meeting at their lower ends and curving upwardly and outwardly. The inlet of arm 12 is in the axial line of the outlet 4 of the member 1 85 in order that a major portion of the stream at maximum velocity may issue from nozzle 14, while a minor portion of the stream passes through the arm 13 and is projected to a less distance. Inserted in the ends of 90 the tubular arms 12 and 13 are tapered tips 14 and 15, which are slightly bent and beveled at their ends to produce rotation of the member 8 by the reaction of the streams leaving tips 14 and 15. 95

The member 1 is also provided with a tubular screen 16 arranged to screen only that water which enters the pipe 5. This screen has open ends and may be a vertically slotted cylinder or consist solely of 100 vertical wires supported by the rings 17 and 18, being thus self-cleaning. The purpose of the screen is to prevent foreign matter from reaching the nozzle member 6, causing wear between the same and the cone 105 10, clogging the opening and possibly interfering with the desired rotation of the member 8.

In the operation of the device shown in Fig. 1, the water leaving the member 1 flows 110 at a considerable increase in velocity over that in the supply pipe. The base of the

rotary member 8 is in axial alinement with the nozzle member 4 and the arms 12 and 13 of the latter gradually curve away from such axial line. Therefore, the jet issuing 5 from nozzle 4 has a practically free path through the rotary member 8. Being only slightly deflected from its normal course, it therefore leaves the latter without giving rise to back pressure in the lower part of 10 the rotary member 8. The design of the passages may be such that the siphonic action of the stream passing through the member 8 will cause a slight flow of air upwardly into the member 8 around the nozzle 15 4 and prevent any leakage at this point. The impact of the stream from nozzle 4 and the frictional action of the water on the member 8 causes the same to be lifted clear of the nozzle 4 and to rotate without mechanical 20 friction between the bell mouth 9 and the nozzle 4. The weight of the member 8 and the action of the downwardly directed stream from the nozzle 6, also prevents contact between the cone 10 and nozzle 25 6. The cone member 10 serves to deflect and spread the stream from nozzle 6 to form a spray, and the heavier streams from the nozzle tips 14 and 15 are thrown to greater and different distances.

30 It may be readily seen that if the cone 10 is raised to completely close the opening 11, the pressure would build up over the entire area of the opening, equal to that in pipe 5, but as soon as the cone 10 is slightly 35 lowered to allow the escape of water, the pressure drops rapidly until a balance is reached, the restricted opening 7 causing this more rapid drop of pressure. Considering the other extreme condition, when the 40 cone 10 is low enough to permit practically a full opening at the opening 11, it is evident that the downward pressure on the cone would be equal only to the pressure, in velocity head, over area 7. It is readily seen 45 that there is an automatic regulation of the cone 10 due to the varying conditions of pressure in the opening 11 for the various positions of the cone.

The attachment shown in Fig. 3 consists 50 of a pair of cone members 36 and 37 similar to the cone 10 but having threaded engagement with a sleeve 38 whereby the cones may be adjusted toward or away from the nozzles 6 and 4. This attachment is intended to be 55 substituted for the member 8 when the device is used for producing a fine spray or mist such as is desirable for seed beds, etc., or for the prevention of frost. The path of 60 the spray is approximately that indicated by the arrows, the two oppositely disposed conical streams meeting and being thus broken up into a finely divided scattering spray. It is intended that these cones be varied in form as indicated in Fig. 4 to suit 65 different requirements.

Fig. 5 shows a modified arrangement comprising a conical stationary nozzle member 19 and a rotary nozzle member 20 having upwardly and outwardly curved passages 21 and vertical passage 22. The rotary 70 member is provided with an apron or skirt 23 which surrounds nozzle 19, and helps to keep the rotary nozzle from being accidentally displaced. The nozzle 19 is supplied by a pipe 24 which has a spider 25 supporting a rod 26 extending upwardly through the vertical passage 22 and carrying at its upper end a curved deflector 27.

In the operation of this device the member 23 is rotated through the reaction of 80 streams leaving the passages 20 and 21, being lifted from the nozzle 20 by the impact of the stream leaving nozzle 19. The jet which issues from the vertical passage 22 strikes the concave surfaces 28 of the deflector 27 and is turned downwardly as indicated by the arrows, striking the curved annular depression 29 on the upper surface of the rotary nozzle member 20, and issuing therefrom in the form of a spreading umbrella-shaped spray. The reaction of this jet on the rotary member 20 assists in balancing the same between the nozzle 19 and the deflector 27. Thus, this device is also devoid of mechanical friction between the 95 stationary and rotary members thereof.

Fig. 6 shows a further modification of the device shown in Fig. 5, differing mainly in the arrangement of the stationary conical deflector 30 on rod 31 and the flared conical 100 outlet aperture 32 in the rotary member 33. Otherwise the operation and support of the rotary member 33 are similar to those of the arrangements shown in Figs. 1 and 5.

Although several modifications are shown, 105 no attempt has been herein made to illustrate all possible embodiments of the invention, and it will be understood that numerous details of the construction shown may be altered or omitted without departing 110 from the spirit of this invention as defined by the following claims.

I claim:

1. A sprinkler, comprising a nozzle member having two opposed outlets, and a spraying device located between said outlets for deflecting the fluid streams issuing therefrom, and being suitably shaped to be rotated through the impact of one of said fluid streams.

2. In a sprinkler, a movable spray member and a stationary member for delivering water thereto, said members having surfaces located to coact with such water to produce upward and downward reactions on 125 said movable spray member whereby the latter will be balanced and supported out of contact with said stationary member.

3. In a sprinkler, a stationary member arranged to deliver a vertically directed jet 130

and a movable spray member adapted to be poised on said jet, said members having surfaces coacting with the jet to produce upward and downward reactions whereby said movable member will be supported out of contact with said stationary member.

4. A sprinkler comprising a pair of opposed stationary nozzles, a rotary nozzle member between and in axial alinement with 10 said stationary nozzles, said rotary nozzle member being supported, balanced and rotated by the jets from said stationary nozzles.

5. A sprinkler comprising a rotary nozzle member, and a stationary nozzle member 15 constructed to project fluid streams against opposite surfaces of said rotary member for supporting, balancing and rotating the latter.

6. A sprinkler comprising a stationary part having a contracted jet orifice at the 20 top and having a branch outlet at one side, a pipe extending upward from said branch outlet and having a downwardly directed jet orifice above and in alinement with the first said jet orifice, a spray member between 25 said orifices, and a screen for said branch orifice, said screen comprising a grating formed of elements disposed only in the direction of flow toward the first said jet orifices whereby said screen will be kept 30 clean by the stream flowing toward said first orifice.

7. A device of the class described, comprising a nozzle member having opposed outlets, and a rotary member located 35 between said outlets and having a surface arranged to be engaged by a fluid stream from one of said outlets and adapted to cause rotation of said rotary member by the action thereon of said fluid stream.

40 8. A device of the class described, comprising a nozzle member having a plurality of opposed outlets, and a rotatable member located between said outlets and having surfaces in position to be engaged by fluid 45 streams from said outlets, said surfaces being suitably shaped to cause said rotary member to be supported and rotated out of contact with said nozzle member.

9. A device of the class described, com-

prising a nozzle member having a plurality 50 of opposed outlets, and a rotary member located between said outlets, said rotary member having a passage therethrough adapted to receive a fluid stream from one of said nozzle members and so deflect such fluid 55 stream as to cause rotation of said rotary member.

10. A device of the class described, comprising a nozzle member having a plurality of opposed outlets, and a rotary member located 60 between said outlets, said rotary member having a plurality of passages therethrough adapted to receive a fluid stream from one of said nozzle members and so deflect such fluid stream as to cause rotation 65 of said rotary member.

11. A device of the class described, comprising a rotary spray device having a plurality of curved passages therethrough, whereby said spray device may be rotated 70 by a fluid stream passing therethrough, and means for projecting fluid streams against opposite surfaces of said spray device, whereby the same may be supported out of contact with said means.

75 12. A device of the class described, comprising a nozzle member, and a spray device located in alinement with said nozzle member and having curved passages therethrough arranged to gradually deflect a fluid 80 stream in diametrically opposite directions from said nozzle member, said passages having a combined cross-sectional area which is greater than the area of the outlet of said nozzle member.

85 13. A sprinkler comprising a stationary part having a jet orifice at the top and having a branch outlet at one side, a pipe extending upwardly from said branch outlet and having a downwardly directed jet orifice 90 above and in alinement with the first said jet orifice, said downwardly directed orifice having a contracted inner portion opening into an enlarged outer portion, and a rotary spray member between said orifices.

95 Signed at Miami this 6th day of August, 1915.

LEONARD SHAW.
